UNITED STATES PATENT OFFICE.

ALFRED BARKER DUFF, OF PITTSBURG, PENNSYLVANIA.

STEAM-BOILER.

SPECIFICATION forming part of Letters Patent No. 764,438, dated July 5, 1904.

Application filed January 22, 1904. Serial No. 190,188. (No model.)

To all whom it may concern:

Be it known that I, ALFRED BARKER DUFF, a subject of the King of Great Britain and Ireland, and a resident of Pittsburg, Allegheny county, State of Pennsylvania, (whose postal address is 5310 Dahlia street, Pittsburg, Allegheny county, State of Pennsylvania,) have invented certain new and useful Improvements in Steam-Boilers, (for which application for 10 British patent has been made January 1, 1904, No. 2,) of which the following is a specification.

My said invention relates to steam-boilers in which steam is raised by means of the heat 15 of gas-producer gases; and it has for its object to improve the heating-surface parts of the boiler, so as to prevent any clogging or choking of these parts, while the arrangements for cleaning, examination, and repair 20 of the boiler parts are also much improved, thereby increasing the efficiency and serviceability of the boiler as a whole. Steam-boilers of this class as usually constructed have hitherto proved unsuccessful owing chiefly 25 to defects connected with the design of the heating-surface parts, the heating-tubes employed in such boilers, owing to their smallness and the manner of their arrangement, soon becoming clogged and choked with soot 30 and dust, which afterward cannot be cleaned out satisfactorily owing to the inaccessibility 35 of the said tubes. My improvements are designed to overcome such defects, and they are shown on the accompanying two sheets of drawings, to be hereinafter referred to in describing the said improvements.

Figure 1, on Sheet 1 of the drawings is a sectional side elevation; and Fig. 2, Sheet 2, a sectional plan of the improved steam-boiler 40 shown as applied to a gas-producer.

In the drawings the same reference-letters are used to mark similar parts.

According to my invention the improved steam-boiler consists of a vertical outer shell 45 or casing A of circular form fitted internally with upper and lower horizontal tube-plates B' B², between which are fixed two pairs or sets of vertical heating-tubes C' C², each tube being large enough to admit a workman for 50 cleaning or repairs. The upper ends of the

tubes C' C² open into an upper space or box D, formed above the upper tube-plate B', such box being arranged with four manhole-doors D' on the top for the purpose of gaining access to the tubes C' C². The lower ends 55 of each pair of tubes C' C² open, respectively, into separate inlet and outlet bottom spaces or boxes E' E², arranged below the bottom tube-plate B² and preferably formed by dividing a single box part into two by means of a cross-partition plate E³, which is lined with fire-brick on its inner side. The outlet-space E² 60 is fitted with a discharge-pipe E⁴ and the inlet-space E' is connected to a brick-lined chamber G, connected to the gas-discharge outlet 65 H of the producer J, the said chamber G being provided with a stop-valve G', operated by means of a hand-wheel G² and spindle G³. Cleaning-doors K are provided on the bottom dust-box parts E' E², a door-fitting being arranged opposite each tube, while a similar door G⁴ is also preferably fitted to the bottom of the inlet valved chamber G. A manhole-door A' is fitted to the outer shell A of the water-chamber part of the boiler to enable 70 admittance to be gained for cleaning or repairs, sufficient room being left between the parts inside the boiler, so as to enable any cleaning, examination, or repairs to be accomplished without difficulty. 75

The boiler A is furnished with the usual valve-pipes and other mountings, and when in use the hot gas coming from the producer J through the inlet-valve G' enters and passes up through the first pair or up-comer set C' of the heating-tubes to the upper box D and then passes down the second pair or down-comer set C² of the tubes and through the outlet bottom space or box E² to the discharge-pipe E⁴. 85

With this improved construction of boiler 90 no clogging or choking of the heating-surface parts can take place, as owing to the vertical arrangement of the heating-tubes C' C² soot and dust will not tend to lodge on the tubes, but will fall into the bottom dust-boxes E' E², 95 from whence it can be easily removed through the cleaning-doors K, arranged thereon, without seriously interfering with the continuous operation of the gas-producer J. Owing also to the large size of the heating-tubes C' C², gas 100

can pass through them for long periods before cleaning or scraping of their surfaces becomes necessary, and when such cleaning is required they are, as has been shown, easily accessible 5 for the purpose. By my improvements, therefore, an exceedingly efficient and workable type of steam-boiler is thus produced, which requires small attention and has excellent facilities provided for cleaning, examination, 10 and repair.

What I claim as my invention is—

1. In steam-boilers having their heating-surfaces connected to a gas-producer, a vertical shell, upper and lower tube-plates therein, 15 an upper box part above the upper tube-plate, heating-tubes fitted vertically between the tube-plates, a dust-box part fitted to the lower ends of the tubes and connected to the gas-producer, substantially as and for the pur- 20 poses herein set forth.
2. In steam-boilers having their heating-

surfaces connected to a gas-producer, a vertical shell, upper and lower tube-plates arranged horizontally therein, an upper box part above the upper tube-plate, manhole-doors on the said box, a set of up-comer and of down-comer heating-tubes fitted vertically between the tube-plates, separate inner and outer dust-box parts fitted respectively to the lower ends of each respective set of heating-tubes, cleaning-doors on the said dust-boxes, a gas-inlet on the inner dust-box connected to the gas-producer, and a gas-outlet on the outer dust-box, substantially as and for the purposes herein set forth. 25 30 35

In testimony whereof I have signed my name to this specification in the presence of two subscribing witnesses.

ALFRED BARKER DUFF.
